UNITED STATES PATENT OFFICE.

ALBERT F. STAPLES, OF ALLIANCE, OHIO.

SALES-BOOK.

No. 884,623.

Specification of Letters Patent.

Patented April 14, 1908.

Application filed October 28, 1907. Serial No. 399,509.

To all whom it may concern:

Be it known that I, ALBERT F. STAPLES, a citizen of the United States, residing at Alliance, in the county of Stark and State of Ohio, have invented certain new and useful Improvements in Sales-Books, of which the following is a specification.

This invention relates to the form and construction of sales-books or pads, particularly 10 of the kind in which a number of leaves printed in the form of blank bills or charge slips are secured together temporarily but are arranged to be torn out when filled in and used to file in an account file or as statements 15 of account for the customers. In connection with sales-books of this kind it is customary to use a score sheet on which the names and amounts of the several bills are entered, so that a summary of the transactions entered 20 on the bills may be kept, and the book and the score sheet are usually carried in a holder or cover for the convenience of the user and to protect them against injury when carried in the pocket. An example of such a holder 25 is disclosed in the inventor's prior patent, No. 835,041, dated Nov. 6, 1906.

The sales-book, as usually constructed, comprises a body of leaves secured to a cardboard back which serves usually as a means 30 for securing the book in the holder. The score sheet is furnished separately, it being necessary to provide a sheet for each book. The pages of the book are numbered consecutively, in pairs to permit duplicating, 35 and the score sheet is printed with spaces numbered consecutively to correspond to the numbers on the bills.

The object of the present invention is to obviate the expense and inconvenience of 40 providing a separate score sheet, and to this end it is proposed to utilize the cardboard back of the pad as a score sheet by making it removable by perforating it or otherwise and by printing it with suitable lines and with 45 serial numbers corresponding to those on the leaves. While the book of which the score sheet forms the back is in use the score sheet serves merely the purpose of the ordinary cardboard back, but when the leaves have 50 been used the back is detached and is used as a score sheet in connection with the next

book, so that each book provides a score sheet for the next.

In the accompanying drawings Figure 1 is a perspective view of a sales-book embodying the present invention, and Fig. 2 is a rear view of the same.

The illustrated embodiment of the invention comprises a body 1 of leaves and a back 2 of cardboard. The leaves are printed, as 60 shown in Fig. 1, in the form of bills, and are provided with serial numbers 3. The back 2 is printed with spaces equal in number to the number of bills, and these spaces are numbered serially as at 4 in Fig. 2, one-half 65 of the spaces and numbers being on each side. A row of perforations or indentations 5 provides for removing the score sheet when the book has been entirely used, and the sheet, when so removed, may be inserted in 70 the cover of the holder in the ordinary manner and used with a new pad carried by the pad holder.

The invention may be embodied in various other forms within the terms and scope of 75 the invention as set forth in the following claims.

1. A sales book comprising a body of leaves printed for use as charge slips, and a back of sheet material secured to the leaves at 80 one edge and having a weakened portion near such edge to facilitate its removal, the back being printed for use as a score sheet, so that when removed it may be used in connection with another similar sales book. 85

2. A sales book comprising a body of leaves printed for use as charge slips and consecutively numbered, and a cardboard back secured to the leaves at one edge and perforated near such edge to facilitate its removal, 90 the back being printed with spaces numbered to correspond with the numbers on the leaves, so that the back, when removed, may be used as a score sheet in connection with another similar sales book. 95

In testimony whereof, I affix my signature in presence of two witnesses.

ALBERT F. STAPLES.
